SERVICE BUILDING

Donald L. Nelson, Aqua Vista, Orinda, Calif. 94563,
and Lynn T. Evans, 2301 Larkin St., San Francisco,
Calif. 94109

Filed Nov. 19, 1969, Ser. No. 20,173

Term of patent 3½ years

Int. Cl. D25—04

U.S. Cl. D13—1

FIG. 1 is a side elevational view of the building embracing our new ornamental design;

FIG. 2 is an end view of the building shown in FIG. 1;

FIG. 3 is the other end view of the building shown in FIG. 1;

FIG. 4 is a top plan view looking down on the building shown in FIG. 1; and

FIG. 5 is a sectional view looking down along line 5—5 shown in FIG. 1.

We claim:

The ornamental design for a service building, as shown.
